UNITED STATES PATENT OFFICE.

JOHN ALBIN BYSTROM, OF BRAINERD, MINNESOTA.

CLASP-BUTTON.

1,293,327.

Specification of Letters Patent.

Patented Feb. 4, 1919.

Application filed March 21, 1918. Serial No. 223,784.

To all whom it may concern:

Be it known that I, JOHN ALBIN BYSTROM, a citizen of the United States, residing at Brainerd, in the county of Crow Wing and State of Minnesota, have invented certain new and useful Improvements in Clasp-Buttons; and I do declare the following to be a full, clear, and exact description of the invention, such as will enable others skilled in the art to which it appertains to make and use the same.

This invention relates to clasp-buttons, and it relates more particularly to an improved collar button and tie holder.

15 The main object of this invention is to provide a simple and efficient device for fastening a collar and supporting the knot or bow of a tie in an elevated position.

Another object is to provide a device of 20 this character without materially departing from the general outline or configuration of an ordinary collar button.

Another object is to provide a device of 25 this character which is easy and convenient to manipulate, strong, durable, thoroughly effective and practical, and which may be manufactured at a comparatively slight cost.

Other objects and advantages may be 30 apparent to persons who read the following details of description in connection with the accompanying drawings, in which—

Figure 1 is a front elevation of a collar 35 fastened with my improved clasp-button, the tie being represented in broken lines;

Fig. 2 is a vertical sectional view along the line 2—2 of Fig. 1;

Fig. 3 is a horizontal sectional view along 40 the line 3—3 of Fig. 2;

Fig. 4 is a view similar to Fig. 3, except that Fig. 3 shows a tie clasped by the device and Fig. 4 omits the tie and shows the device in its fully closed position;

45 Fig. 5 is a view similar to Figs. 3 and 4, except that the device is shown in its open position ready to receive the tie, a finger being indicated in the position for pressing the base of the flexible and resilient element 50 of the device in the direction indicated by the arrow; and

Fig. 6 shows the complete device in perspective and separate from the article to be fastened thereby.

55 Referring to these drawings in detail, in which similar characters correspond with

similar parts throughout the several views, the collar 1, tie 2, and neck-band 3 are not described in detail, being of ordinary construction and not being a part of this invention. The clasp-button comprises an integral member formed of resilient metal and consists of a disk or base 4 and a pair of clamping jaws 5. Each of the clamping jaws comprises a head portion 6, a neck 65 portion 7 and inwardly converging connecting portions 8, the latter being united with the neck portion 7 and with the perimeter of the disk or base 4 at the perimeter of the latter, but being otherwise disjoined from the base 4 and from the other elements of the device. The base 4 is preferably circular and relatively thin, so as to constitute an inner head of the button, and also to provide a relatively broad surface against 70 which the finger or thumb of the user may be pressed for causing the jaws 5 to separate when it is desired to clasp a portion of the tie therebetween, as is illustrated in Fig. 3. This spring element 4 constantly tends to 80 hold the jaws 5 together, so that when the same is released by the hand of the user, the tie is clasped with efficient pressure and friction to prevent the tie from slipping downwardly from its elevated position.

85 From the foregoing description, it will be seen that I have provided a device which is fully capable of performing the dual functions of a collar button and a tie support, without sacrificing any of the advantages of 90 a collar button of ordinary construction.

Although I have described this embodiment of my invention very minutely, it is to be understood that my invention is not limited to these exact details of construction, 95 but that I am entitled to make such minor changes which do not depart from the inventive idea disclosed in the foregoing description and in the appended claims.

What I claim as my invention is:

100 1. A clasp-button comprising a pair of complementary jaws shaped and combined to form a collar-button-head and tie-clamp, and a spring element constantly tending to press said jaws together and being operable 105 to move said jaws away from one another.

110 2. A clasp-button comprising a flexible and resilient base, and a pair of complementary jaws shaped and combined to form a collar-button-head and tie-clamp, said base serving to retain the button in a button-hole and constantly tending to press said jaws

- together and operable by a deflection thereof to move said jaws away from one another.
3. A clasp-button comprising a pair of complementary jaws shaped and combined to form a collar-button-head and tie-clamp, and a spring element integrally united with said jaws and constantly tending to press said jaws together and being operable to move said jaws away from one another.
- 10 4. A clamping device comprising a disk of relatively thin and springy material, a pair of clamping jaws disposed substantially parallel with a line perpendicular to the center of said disk and a pair of connecting portions having their outer edges united with the perimeter of said disk and extending toward the said clamping jaws and unit-
- 15

ing therewith and being inwardly convergent, each of said clamping jaws being of a width substantially equal to the width of the 20 inner end of the contiguous clamping jaw and considerably less than the breadth of said disk, said disk being effective to yieldingly press said jaws toward one another and being operable to separate said jaws, 25 substantially as described and illustrated.

In testimony whereof I have hereunto set my hand in the presence of two subscribing witnesses.

JOHN ALBIN BYSTROM.

Witnesses:

CLIFTON A. ALLBRIGHT,
J. H. KREKELBERG.
